SLEEPING CAR

Robert A. Shields, Bloomsburg, Pa., assignor to
American Car and Foundry Company, New
York, N. Y., a corporation of New Jersey

Application July 25, 1946, Serial No. 686,243

12 Claims. (Cl. 105—315)

1

This invention relates to sleeping cars in general and in particular to sleeping cars having separate rooms with complete accommodations therein.

Quite a number of railway cars have been built with room type accommodations with the rooms intended for occupancy either by one or, in the case of so-called bedroom cars, by more than one person. To date, however, sleeping accommodations of the room type adapted for occupancy by more than one person have been rather expensive. In certain cases single occupancy rooms have been occupied by two people but such an arrangement is extremely uncomfortable and the railroads cannot charge for the extra person since no true accommodations have been provided. Since it costs the railroads a certain amount to haul a car, it is obvious that the greater the number of passengers, the lower the rate per person can be charged, while at the same time returning a greater revenue to the railroad. It is an object, therefore, of the present invention to provide a sleeping car having rooms on either side of the aisle of single occupancy size, yet having accommodations for two persons.

A further object of the invention is the provision of a sleeping car having single occupancy size rooms with two beds therein.

A still further object of the invention is the provision of a railway car having complete rooms each containing two vertically movable beds.

Yet another object of the invention is the provision of a railway car having vertically movable beds which remain horizontal at all times and are rigidly supported at four points when in a sleeping position.

Still another object of the invention is the provision of vertically movable beds carried by screw means and equipped with slot closers which hide the screw operating means.

These and other objects of the invention will be apparent to persons skilled in the art from a study of the following description and accompanying drawings, in which

Fig. 1 is a sectional view taken through the car and showing the rooms in plan;

Fig. 2 is an elevational view of one end wall of a room with parts removed to better show the construction and with beds shown in their lowered position;

Fig. 3 is an elevational sectional view taken through the room and showing the aisle wall of the room;

Fig. 4 is a sectional view similar to Fig. 2 but showing the opposite end of the room and with the beds in raised and locked position;

2

Fig. 5 is an enlarged plan view of the room;

Fig. 6 is a similar enlarged plan view showing the bed operating means;

Fig. 7 is an enlarged detail view taken substantially on line 7—7 of Fig. 8 and showing the bed support and slot closer;

Fig. 8 is a sectional view taken substantially on line 8—8 of Fig. 7;

Fig. 9 is an enlarged detail view showing the nested relationship of the beds during raising or lowering;

Fig. 10 is a sectional view taken through the room partition and showing the bed in its sleeping position;

Fig. 11 is a detail view showing the lock means for the upper bed, and

Fig. 12 is a sectional view taken through the room partition and showing the locking means for the beds.

Referring now to the drawings in detail, it will be seen that the car is built with side walls 4, end walls 6, floor 8 and roof 10. Located inside the car are longitudinally extending aisle walls 12 having openings therein preferably closed by sliding doors 14. Extending between the side walls and the adjacent aisle walls are spaced partition walls 16 which, together with the car side walls and aisle wall, form the walls of the separate rooms. By arranging the parts as later to be described, it is possible to obtain twelve rooms on either side of the aisle in a railway car having a length of 85 ft. over buffers which at present is the generally accepted standard. Each room as shown is equipped with two beds B, folding chair C and wardrobe W, beneath which is located a shoe locker S having an opening into the aisle. Each room is also equipped with a cabinet M for medicines or toilet articles and also with a folding washbasin and lavatory L and hopper H. The wardrobe and shoe locker

is located a shoe locker S having an opening into the aisle. Each room is also equipped with a cabinet M for medicines or toilet articles and also with a folding washbasin and lavatory L and hopper H. The wardrobe and shoe locker

may be made as a separate cabinet for placement in the room, as may also the hopper, lavatory and medicine cabinet. As shown the wardrobes and folding wash basin units are located along the aisle wall on either side of the sliding door 14. As shown the hopper units are preferably arranged adjacent each other in adjacent rooms in order that the plumbing may be simplified. It is obvious, of course, however, that these units may be placed along the outer side wall of the car, although such a placement will cut down on the space available for persons standing in the entrance to the room while the beds are being raised or lowered.

As shown the beds indicated at B #1 and B

#2 are of identical size and extend substantially from one partition wall 16 to the opposite partition wall 16. The partition walls at one end of the room are provided with slots 20 located closer to the side walls and aisle walls than are slots 22 formed in the partition wall 16 at the opposite end of the room and as shown in Fig. 4. Bed B #1 is provided at one end with widely spaced arms 24 extending through slots 20, while bed B #2 is provided at one end with arms 26 extending through the same slots 20. The opposite ends of beds B #1 and B #2 are provided with closer spaced arms 28 and 30 respectively extending through slots 22. The arms 24 and 28 of each lower bed B #1 are internally threaded to engage the threads 32 of lead screws 36 rotatably mounted at their lower ends in blocks 38 and guided at their upper ends by shaft supports 40. The shaft supports 40 and blocks 38 are fastened to and tie the partition wall 16 of adjacent rooms together, thereby reinforcing the partitions while at the same time forming supports for the lead screws 36. The arms 26 and 30 of the upper bed B #2 are provided with smooth holes 42 therethrough, which holes are adapted to closely engage the outer surface of threads 32 in order that the lead screws 36 may guide the arms 26 and 30. Each arm 26 and 30 is also provided with an extension 44 adapted to engage a conical extension 46 formed on the upper surface of arms 24 and 28 of the lower bed B #1. The arms 24 and 28 of bed B #1 are identical, while the arms 26 and 30 of bed B #2 are also identical except that arms 26 are provided with outwardly projecting stop lugs 48, while arms 30 are provided with inwardly projecting stop lugs 50.

In order to rotate the lead screws 36 for each room in unison they have fastened thereto at their upper ends bevel gears 52 adapted to engage bevel gears 54 carried on transverse shafts 56. The transverse shafts 56 are also provided with intermediate bevel gears 58 adapted to mesh with bevel gears fastened to a longitudinally extending intermediate shaft 60. One of the transverse shafts or the longitudinal shaft 60 is driven directly by a motor 62. This motor may be of small fractional horse power due to the use of the gearing and lead screws. It is obvious that with all of the lead screws 36 for each room interconnected by gearing or similar means, they must rotate in unison thereby causing the arms 24 and 28 of the bed B #1 to be moved in a vertical direction in unison thereby holding bed B #1 always horizontal. Rotation of motor 62 will, of course, be under control of a push button or other type switch located in the room with which the motor is associated.

Since the lead screws 36 will positively hold bed B #1 in any position in which it is stopped, no locks will be necessary for bed B #1. Bed B #2, however, since it is not connected to the lead screws but merely slides therealong, must be equipped with locks or other holding means to keep it from being lowered when it is desired to sell the room to a single person. Arms 26 of bed B #2 may be locked in their upper or raised position by means of a transversely sliding bolt 70 actuated by lever 72 connected by cables or other means 74 to a cam member 76 accessible from the inside of the room. The sliding bolt 70 when thrown into locking position as shown in Fig. 11 will engage beneath stop ledge 48 of arm 26. Arms 30 at the opposite end of the bed B #2 will be held in raised position by means of sliding

bolts 80 engaging beneath stops 50 of arms 30. The sliding bolts 80 may be simultaneously operated by means of linkage 82 connected to a throw arm 84 controlled by a key or other means from the inside of the room. The locking means for the upper bed B #2 is shown in the unlocked position in Fig. 2 and in the locked position in Fig. 4. It will be obvious that with the locks as shown it will be necessary to insert a special key at three positions in each room before the upper bed B #2 can be unlocked and these locks are preferably under control of the car porter and impossible to be operated by the occupants of the room. In order to stop and hold bed B #2 in its lowered or sleeping position locks 90 are fastened to the partition walls 16 and tie the adjacent partition walls together, thus stiffening the same while providing rests upon which the bed B #2 will be held when in lowered position.

For smooth easy operation of the beds it will, of course, be desirable that the lead screws 36 be well oiled either with grease or graphite, and since the slots 20 and 22 are necessary to accommodate the bed arms, it will be obvious that the bedding might become soiled, but in any case the slots would be very unsightly. In order to cover these slots fabric 92 is attached to the partition walls on either side of the slot and this fabric has secured thereto metal fasteners 94 of the well known slide fastener type. Each of the arms of the beds or the beds themselves have attached thereto adjacent the arms slide fasteners 96. Normally, the slide fasteners are closed thereby hiding the slot and the lead screw. During movement of the beds, however, one slide fastener will cause the fabric parts to separate and the other will cause the parts to again be closed. Since these slides will be located in the plane of the bed to which they are attached, it is obvious that anyone watching the operation of the bed will never see anything except the closed fabric both above and below the moving bed.

The under surface of beds B #1 and B #2 is finished so as to blend into the room decorations and may carry lights supplied by current either directly through the lead screws or through sliding contacts. In this way overhead lights will be provided for the room and due to the position of the beds in the ceiling zone the ceiling will necessarily be much lower than the average room now in use on the railroads. Such low ceiling will give the effect of increasing the dimensions of the room, that is, to a person occupying the room it will seem much larger than does a high ceiling room.

From the preceding description it will be seen that a car has been provided with a large number of rooms therein having beds for individual occupancy extending longitudinally of the car and moving from an inoperative position in the ceiling of the room to an operative position between the floor and ceiling. In case the room is being occupied by a single person it is only necessary to fold the chairs C and close all cabinet doors, after which a switch may be operated causing rotation of motor 62. This motor is, of course, of the reversible type and when rotating in the lowering direction will cause the screws 36 to rotate in such a direction as to lower bed B #1 which is directly connected to the lead screws. The motor will continue to operate until bed B #1 has been completely lowered and comes to rest upon blocks 38. Safety devices (not shown) may be applied either to the motor or to blocks 38 so as to stop rotation of the motor when the bed B #1 comes to rest.

upon the blocks. In case there are two persons occupying the room the conductor or porter will at the time of taking tickets unlock the top bed B #2 by rotation of lock members 76 and 84. When the top bed has been unlocked and the occupants of the room desire the bed in operative position the same lowering button or switch will again be operated and beds B #1 and B #2 will lower as a unit until bed B #2 comes to rest in its operative position through the engagement of ledges 49 or 50 with stop lugs 99 fastened to the partition walls. Bed B #1 will continue lowering until it has come to rest upon blocks 38. Reversal of the motor will cause the lowered beds to be moved into the ceiling position. In case the bed B #1 only has been lowered it will travel directly up to its final position as shown in Figs. 3 and 4 in which its under surface forms the ceiling of the room. In case, however, bed B #2 is in the lowered position bed B #1 will move upwardly until the conical surfaces 46 of its arms engage the extensions 44 of bed B #2, after which the two will rise as units to their final stored position. The locks for the bed B #2 preferably will not engage the arms of bed B #2 automatically, but must be moved to their locked position by the conductor or car attendant. During the raising and lowering of the beds, whether singly or in unison, the slots 20 and 22 will appear to be closed due to the slot closers attached either to the bed or to the bed arms, thus the room will always display substantially smooth end walls without any unsightly slots or operating mechanism being visible. It is, of course obvious that spring pressed metal flaps or resilient material such as rubber may be used in place of the fabric with attached slide fasteners to close these slots.

While the improved bed arrangement has been described more or less in detail with specific reference to the figures, it is obvious that various modifications, other than those shown and described, may be made and all such modifications are contemplated as will fall within the scope of the following claims.

What is claimed is:

1. A railway car having a central aisle defined by aisle walls, space between the aisle walls and side walls, pairs of transverse partitions dividing said space into rooms with one partition of adjacent pairs defining the end walls of a room, vertical slots in said transverse partitions, a bed positioned horizontally in the room and substantially filling the space between the four walls of the room, arms extending from the bed through said slots, and operating means located between the partitions constituting a pair at each end of a room, said operating means engaging said arms whereby said bed may be moved vertically from an operative to an inoperative position wherein the under surface forms the ceiling of the room.

2. A railway car having a central aisle defined by aisle walls, space between the aisle walls and side walls, pairs of transverse partitions dividing said space into rooms with one partition of adjacent pairs defining the end walls of a room, vertical slots in said transverse partitions, a bed positioned horizontally in the room and substantially filling the space between the four walls of the room, arms extending from the bed through said slots, operating means located between the partitions constituting a pair at each end of a room, said operating means engaging said arms whereby said bed may be moved vertically from an operative to an inoperative position wherein the under surface forms the ceiling of the room, and means

closing said slots substantially throughout their length except in the immediate zone of said arms.

3. A railway car having a central aisle defined by aisle walls, space between the aisle walls and side walls, pairs of transverse partitions dividing said space into rooms with one partition of adjacent pairs defining the end walls of a room, vertical slots in said transverse partitions, a bed positioned horizontally in the room and substantially filling the space between the four walls of the room, arms extending from the bed through said slots, operating means located between the partitions constituting a pair at each end of a room, said operating means engaging said arms whereby said bed may be moved vertically from an operative to an inoperative position wherein the under surface forms the ceiling of the room, slide fastener means closing said slots to conceal said operating means, and operators for said slide fasteners secured to said bed to open and close said slide fastener means in accordance with the movement of the bed.

4. A railway car having a central aisle defined by aisle walls, space between the aisle walls and side walls, pairs of transverse partitions dividing said space into rooms with one partition of adjacent pairs defining the end walls of a room, vertical slots in said transverse partitions, a first bed positioned horizontally in the room and substantially filling the space between the four walls of the room in the plane of the bed, a second bed of substantially the same dimensions positioned above said first bed, said beds being in contact when in inoperative position with the lower surface of the first bed forming the ceiling for the room, arms extending from the beds through said slots, operating means located between the partitions constituting a pair at each end of a room and being in engagement with said bed arms whereby the beds may be moved vertically in the room.

5. A railway car having a central aisle defined by aisle walls, space between the aisle walls and side walls, pairs of transverse partitions dividing said space into rooms with one partition of adjacent pairs defining the end walls of a room, vertical slots in said transverse partitions, a first bed positioned horizontally in the room and substantially filling the space between the four walls in the plane of the bed, a second bed of substantially the same dimensions positioned above said first bed, said beds being closely adjacent each other when in their inoperative position with the lower surface of the first bed forming the ceiling for the room, screw means located between the partitions constituting a pair at each end of a room and accessible through said slots, and arms secured to said beds and extending through said slots into engagement with said screws, the arms of said first bed having threaded engagement with said screw means whereby the first bed may be raised or lowered and the arms of said second bed having sliding engagement with the screw means.

6. A railway car having a central aisle defined by aisle walls, space between the aisle walls and side walls, pairs of transverse partitions dividing said space into rooms with one partition of adjacent pairs defining the end walls of a room, vertical slots in said transverse partitions, a first bed positioned horizontally in the room and substantially filling the space between the four walls in the plane of the bed, a second bed of substantially the same dimensions positioned above said first bed, said beds being closely adjacent

each other when in their inoperative position with the lower surface of the first bed forming the ceiling for the room, screw means located between the partitions constituting a pair at each end of a room and accessible through said slots, and arms secured to said beds and extending through said slots into engagement with said screws, the arms of said first bed having threaded engagement with said screw means whereby the first bed may be raised or lowered and the arms of said second bed having sliding engagement with the screw means, and means to retain said second bed in raised position independent of the raising or lowering of said first bed.

7. A railway car having a central aisle defined by aisle walls, space between the aisle walls and side walls, pairs of transverse partitions dividing said space into rooms with one partition of adjacent pairs defining the end walls of a room, vertical slots in said transverse partitions, a first bed positioned horizontally in the room and substantially filling the space between the four walls in the plane of the bed, a second bed of substantially the same dimensions positioned above said first bed, said beds being closely adjacent each other when in their inoperative position with the lower surface of the first bed forming the ceiling for the room, screw means located between the partitions constituting a pair at each end of a room and accessible through said slots, and arms secured to said beds and extending through said slots into engagement with said screws, the arms of said first bed having threaded engagement with said screw means whereby the first bed may be raised or lowered and the arms of said second bed having sliding engagement with the screw means, and means to retain said second bed in an intermediate position in the room and in vertically spaced relationship to said first bed when lowered into an operative position.

8. A railway car having a central aisle defined by aisle walls, space between the aisle walls and side walls, pairs of transverse partitions dividing said space into rooms with one partition of adjacent pairs defining the end walls of a room, vertical slots in said transverse partitions, a first bed positioned horizontally in the room and substantially filling the space between the four walls in the plane of the bed, a second bed of substantially the same dimensions positioned above said first bed, said beds being closely adjacent each other when in their inoperative position with the lower surface of the first bed forming the ceiling for the room, screw means located between the partitions constituting a pair at each end of a room and accessible through said slots, and arms secured to said beds and extending through said slots into engagement with said screws, the arms of said first bed having threaded engagement with said screw means whereby the first bed may be raised or lowered and the arms of said second bed having sliding engagement with the screw means, and means to retain said second bed in raised position independent of the raising or lowering of said first bed, said means being releasable to permit said second bed to be lowered during partial lowering of said first bed.

9. A bed arrangement comprising fixed vertical end walls in spaced apart relation, vertical

slots extending through said end walls, operating means located adjacent said slots and on the opposite side of the end walls from the space therebetween, a bed substantially spanning the

5 space between end walls, arms secured to said bed and extending through said slots into engagement with said operating means for vertical movement thereby, and means closing said vertical slots above and below said arms in unison with and during vertical movement of the arms.

10. A bed arrangement comprising fixed vertical end walls in spaced apart relation, vertical slots extending through said end walls, operating means located adjacent said slots and behind the

15 plane of the end walls, a bed substantially spanning the space between end walls, arms secured to said bed and extending through said slots into engagement with said operating means for vertical movement thereby, and means closing said vertical slots above and below said arms during vertical movement of the arms, said means including a slide fastener opening ahead of and closing behind said arms in accordance with the vertical movement of said bed arms.

20. 11. A bed arrangement comprising vertical end walls, vertical slots in said end walls, operating means located adjacent said slots and behind the plane of the end walls, a first bed, a second bed above said first bed, both said beds substantially

25 spanning the space between said end walls, arms secured to said beds and extending through said slots into engagement with said operating means, the arms of said first bed being vertically movable by said operating means to raise and lower

30 the bed while the arms of said second bed have sliding movement relative to the operating means, and means selectively retaining said second bed in raised position during lowering of said first bed.

35 12. A bed arrangement comprising vertical end walls, vertical slots in said end walls, operating means located adjacent said slots and behind the plane of the end walls, a first bed, a second bed above said first bed, both said beds substantially

40 spanning the space between said end walls, arms secured to said beds and extending through said slots into engagement with said operating means, the arms of said first bed being vertically movable by said operating means to raise and lower

45 the bed while the arms of said second bed have sliding movement relative to the operating means, means selectively retaining said second bed in raised position during lowering of said first bed, and additional means retaining said second bed in a preselected lowered position during continued lowering of said first bed.
